UNITED STATES PATENT OFFICE.

HOWARD L. HAYFORD, OF WHITMAN, MASSACHUSETTS.

COLLAPSIBLE LIFE-RAFT.

1,263,764.

Specification of Letters Patent. Patented Apr. 23, 1918.

Application filed January 14, 1918. Serial No. 211,713.

To all whom it may concern:

Be it known that I, HOWARD L. HAYFORD, a citizen of the United States, residing at Whitman, in the county of Plymouth and State of Massachusetts, have invented new and useful Improvements in Collapsible Life-Rafts, of which the following is a specification.

This invention relates to a life raft which includes a buoyant body of annular or like continuous form, the body being frame-shaped and surrounding an opening, a bottom adapted to be stored or nested in said opening to collapse the raft, and flexible suspending means connecting the bottom with the body, and adapted to support the bottom in a plane below the body when the raft is in use, the suspending means being movable with the body to permit the necessary movements of the body in collapsing and extending the raft.

The invention has for its object to simplify and reduce the expense of constructing a raft of this character, and relates particularly to the suspending means connecting the bottom with the body.

The invention is embodied in the improvements which I will now proceed to describe and claim.

Of the accompanying drawings, forming a part of this specification,—

Figure 1 is a side view of a collapsible raft embodying the invention, the raft being operatively extended.

Fig. 2 is a plan view of the same.

Fig. 3 is a side view of a portion of the elongated strip hereinafter described, from which the suspending device is formed.

Fig. 4 is a sectional view of a portion of the body, and shows the strip as applied to the body prior to its attachment to the bottom.

Fig. 5 is a section on line 5—5 of Fig. 2.

Fig. 6 is a view similar to Fig. 5, showing the bottom moved into the opening surrounded by the body.

Fig. 7 is a fragmentary perspective view of a portion of the suspending device, in its operative position, the buoyant body and the bottom being shown by dotted lines.

The same reference characters indicate the same parts in all of the figures.

In the drawings 12 designates a continuous annular buoyant body or float, preferably of elliptical form as shown by Fig. 2. Said body may be of any suitable buoyant

construction and may include an inner air tube of thin sheet metal and a tubular covering of cork, or other suitable buoyant material, applied exteriorly to the inner tube. 60 As buoyant bodies of this character are well known in life rafts, further description of the construction thereof is unnecessary.

13 designates a bottom adapted to support the occupants of the raft and formed 65 to enter the opening surrounded by the body, so that the raft may be collapsed, as indicated by Fig. 6. The bottom may be of any suitable construction.

The body 12 and bottom 13 are connected 70 by a flexible annular suspensory attached to the margin of the bottom and formed to loosely embrace the body and to slip circumferentially thereon, when the bottom is moved sidewise relatively to the body. The 75 suspensory is formed and adapted to support the bottom at a plane below the plane of the body, as indicated by Figs. 1 and 5, and is caused to slip circumferentially on the body, when the bottom is moved into 80 the opening surrounded by the body, as indicated by Fig. 6.

The preferred construction of the suspensory is as follows:

I take an elongated strip 14 of any suitable flexible material, preferably rope or cord netting, of relatively coarse mesh and provided with selvage edges. I couple together the transverse edges or ends 14^a of the strip to form a seam, indicated at 15 90 (Fig. 2), and then fold the now continuous strip over the body 12, as indicated by Fig. 4, the longitudinal edges 14^b of the strip hanging parallel with and below the body. Finally, I attach the longitudinal edge portions of the strip to the margin of the body by any suitable fastening means such as nails or screws 16, the binding strip 17 being preferably placed upon the outer layer of the folded body, in position to receive 100 the attaching devices.

It will now be seen that the strip 14 constitutes a suspensory formed as a continuous annular bag, loosely embracing the body and adapted to slip circumferentially thereon 105 when the bottom is moved sidewise relatively to the body. The width of the strip 14 is such that the suspensory is adapted to support the bottom in a plane considerably below the plane of the body. The freedom 110 of the suspensory to slip circumferentially on the body enables the bottom to be freely

5 moved into and out of the opening surrounded by the body, the bag-shaped suspensory offering practically no resistance to such movement. The portion of the annular bag which is seated on the upper portion of the body 12 constitutes a central zone, and the portions which depend from the body constitute inner and outer zones.

10 While the strip 14 may be made of any suitable flexible material such as canvas, I prefer open mesh netting, the intersecting strands of which are inclined relatively to the longitudinal edges 14^b of the strip, because this material is adapted by its reticulated structure and by the arrangement of its strands to be spread smoothly over the upper portion of the body 12 and to depend smoothly therefrom without folds or creases, as shown by Fig. 7. From this figure it will 15 be seen that the meshes of the vertical inner zone depending from the body are vertically elongated and laterally contracted, while the meshes of the inclined outer zone depending from the body are vertically contracted and 20 laterally enlarged, and the meshes of the intermediate zone seated on the upper portion of the body, lie smoothly on the body, there being an entire absence of overlapping folds or creases in either zone. The reticulated 25 strip, therefore, forms an annular bag which includes smooth inner and outer wall portions, and a smooth intermediate portion adapted to accurately conform to and slip freely on the body 12.

30 35 Moreover, the netting is adapted to pass freely with the bottom into or through the opening surrounded by the body without liability of fouling or causing the bottom to bind within the body, so that the raft is 40 adapted to be quickly extended or rendered operative.

I claim:

45 1. A collapsible life raft comprising a buoyant annular body, a bottom formed to enter the opening surrounded by the body, and a flexible annular suspensory formed

from an elongated strip of flexible material and including a central zone which is seated on the upper portion of the annular body when the bottom is depressed below said body, and inner and outer zones depending from the central zone, converging therefrom to the margin of the bottom, and attached to said margin.

2. A collapsible life raft comprising a 55 buoyant annular body, a bottom formed to enter the opening surrounded by the body, and a flexible annular suspensory composed of an elongated strip of flexible material folded over the body, attached at its longitudinal edges to the margin of the bottom, and coupled together at its transverse edges, said strip forming a continuous annular bag, loosely embracing the body and adapted to slip circumferentially thereon when the bottom is moved sidewise relatively to the body, said annular bag including a central zone which is seated on the upper portion of the annular body when the bottom is depressed below said body, and inner and outer zones 60 65 depending from the central zone, converging therefrom to the margin of the bottom, and attached to said margin.

3. A collapsible life raft comprising a 70 buoyant annular body, a bottom formed to 75 enter the opening surrounded by the body, and an elongated strip of open mesh netting formed into an annular bag, and having its intersecting strands inclined relatively to the longitudinal edges of the strip, said 80 bag including a central zone which is seated on the upper portion of the body when the bottom is depressed below the body, and inner and outer zones depending from the central zone, converging therefrom to the margin of 85 the bottom, and attached to said margin, the inclination of said strands permitting the bag to conform to the body and depend therefrom without folds or creases.

90 In testimony whereof I have affixed my signature.

HOWARD L. HAYFORD.
